UNITED STATES PATENT OFFICE

HORACE H. BURDETT, OF HOPEDALE, MASSACHUSETTS, ASSIGNOR TO DRAPER CORPORATION, OF HOPEDALE, MASSACHUSETTS, A CORPORATION OF MAINE

INTERMITTENT THREAD-CUTTING TEMPLE

Application filed June 5, 1929. Serial No. 368,687.

This invention relates to a mechanism for trimming off close to the selvage the filling ends left projecting therefrom during the weaving operation. Such ends occur particularly as a result of the operation of the automatic filling replenishing loom wherein each time the filling is changed or replenished both the discharged filling carrier and the fresh filling carrier leave ends projecting at the selvage which must be removed. In the present invention the filling severing mechanism is carried by the shank or bodily movable member of the usual temple and is operated intermittently, as, for example, at the time of filling replenishment, so that the filling severing mechanism is not subject to the wear due to continuous operation but only acts occasionally and during the short periods required to effect the trimming off of the filling ends.

The object of the invention is to provide an intermittent filling severing mechanism in which, when this mechanism is in inactive position, it shall be held out of engagement with the lay or other actuating part of the loom and in which its withdrawal to this position shall be effected by the relative sliding movement between the temple stand and temple shank.

The object of the invention is further to provide simple, novel and effective means for securing the intermittent operation of the filling severing mechanism.

The object of the invention is further to provide an intermittently operating selvage trimming mechanism carried by the temple in which the filling severing mechanism is bodily and laterally adjustable to position it close to the selvage.

The nature and objects of the invention will appear more fully from the accompanying description and drawings and will be particularly pointed out in the claims.

As the invention is applicable to various type of looms and is concerned only with the severing of the filling ends of the selvage, it is only necessary here to illustrate and describe a preferred form of the invention and those parts of an ordinary type of automatic

filling replenishing loom immediately associated therewith.

In the drawings:

Fig. 1 is a side elevation partially in cross section of a portion of a loom with the temple of an ordinary type mounted thereon and with a preferred form of the invention embodied therein. 55

Fig. 2 is a top plan view of the construction shown in Fig. 1. 60

Fig. 3 is a detail chiefly in vertical cross section taken on the line 3—3 of Fig. 2.

Fig. 4 is a detail in side elevation showing detent mechanism. 65

Fig. 5 is a detail in cross section taken on the line 5—5 of Fig. 3.

In the construction of loom illustrated, the side frame 1, to which the usual breast beam 2 is connected, carries the usual starting rod 3 from which extends upward an arm 4. In the automatic type of filling replenishing loom such a starter rod 3 is commonly employed and, upon the call for filling replenishment, is rocked in a direction to swing the arm 4 to the left. The lay 5 of the loom is illustrated carrying the usual reed 6 and acting to beat the filling into the cloth 7 at the fell 8 in the usual manner. 75

An ordinary type of temple is shown mounted on the breast beam and extending rearward to act upon the cloth forward of the fell. This temple is shown as comprising a box-like stand 9 carried by a bracket 10 secured to the breast beam 2 and a shank 11 mounted to slide in the stand 9. This shank is normally projected rearward by the usual spring 12 in the stand and is given a slight forward sliding movement in the stand by the engagement of the lay 5 of the loom at each beat-up with a heel 13 rigid with and depending from the shank. At its rearward end the shank is formed to present the usual temple head 14 from which projects laterally the usual cap 15 and pod 16 between which is journaled the temple roll 17. 95

While the filling severing mechanism may be of various types so far as certain features of the present invention are concerned, it is preferably of that type in which it is bodily adjustable laterally with respect to the shank 100

so as to enable the cutting operation to be performed close up to the selvage of the cloth. Since the cloth as it passes around the temple roll has the selvage extending between the planes of the ends of the temple roll, the filling severing mechanism, when laterally adjusted to sever the filling ends close to the selvage, also has its field of action between the planes of the ends of the temple roll.

10 In the preferred construction illustrated, the shank 11 which forms the support for the filling severing mechanism has mounted therein a rod 18 extending laterally just forward of the temple head and above the plane of the cloth. This rod at its outer end is threaded and provided with a nut 19. Forward of this rod the shank of the temple is formed with a hub 20 and in this hub a shaft 21 extending parallel with the rod 18 is mounted to slide and rotate.

15 The severing mechanism comprises a pair of cooperating cutter blades which operate in a plane substantially normal to the path of the cloth and which at their effective portions stand substantially parallel to the selvage forward of the fell. In the construction illustrated, one of these blades is a relatively fixed blade and the other a relatively movable blade, while the two blades together 20 also have a bodily lateral movement or adjustment to enable their effective portions to be positioned and maintained close to the selvage.

25 The fixed cutter blade member is shown as a metal plate 22 recessed at its bottom edge to fit over the temple head. This plate has formed thereon or rigid therewith a long hub 23 which extends laterally therefrom and is mounted to slide on the rod 18. This plate is 30 also apertured at its forward end to fit over the shaft 21. At its rear end the plate 22 is formed into a narrow vertical finger 24 adapted to rest against the edge 25 of the cloth and presents a notch 26 in the plane of the cloth to receive the filling end as the cloth 35 advances in the weaving operation. The cutting edge of the fixed blade 22 is presented by the edge of this notch 26, and the finger 24 may be formed of a separate piece of hardened 40 steel 27 secured to the blade 22.

45 The movable cutter blade 28 is shown as of general hook shape also fitting over the temple head in general parallelism with the fixed blade. Its extreme rear end is bevelled off to present a cutting edge 29 to cooperate with the cutting edge of the notch 26 in the fixed cutter blade. This movable blade 28 is shown as secured to the shaft 21 and thus as pivotally mounted in the shank 11. The 50 movable blade is held in close contact with the fixed blade preferably by means of a stud 30 secured in the movable blade 28 and projecting through a slot 31 in the fixed blade 22 and by a coiled spring 32 surrounding the stud 30 and extending between the fixed blade

55 22 and a washer secured by a cotter pin at the end of the stud 30. This movable cutter blade is preferably made of steel.

60 The opening movement of the severing mechanism, in the construction illustrated, is effected by a spring 33 located in a recess in the fixed blade 22 having one end abutting the lower end of said recess and therefore fixed and the other end abutting the stud 30 and thus acting normally to raise the movable cutter blade 28. The extreme limits of movement of the blade 28 may be determined by the length of the slot 31. The closing movement of the filling severing mechanism by which the filling ends are severed, in the preferred construction illustrated, is secured by the lay 5 engaging and moving forward a depending heel 34, which thereupon acts to swing the movable cutter blade 28 downward to close over the cutting edge of the notch 26 and thus sever any filling ends extending in its path.

65 The entire severing mechanism is adjustable to locate the blades close up against the selvage forward of the fell by adjusting the nut 19 on the rod 18, a spring 35 on the rod between the shank and the fixed blade 22 tending to slide the entire severing mechanism in the direction of the nut and either 70 against the selvage or against the nut. This spring 35 is preferably of a light character and may be arranged so that it will press the severing mechanism to maintain the finger 24 against the selvage 25. In such case, the nut 19 acts simply as a stop to limit the inward 75 movement which is assisted by the shock and jar of the loom and thus enables the severing mechanism to be maintained against the selvage and to shift laterally with any change 80 in the path of the selvage.

85 It is desirable, in view of the mechanism employed for securing intermittent operation of the severing mechanism, that the depending heel 34 shall be located in fixed lateral position and not partake of any lateral movement or adjustment of the filling severing mechanism. As a convenient means for accomplishing this result, the shaft shown generally at 21 in Fig. 2 is made in two telescoping, relatively non-rotatable sections, one secured to the depending heel 34 and the other secured to the movable cutter blade 28. This construction is shown in detail in Fig. 5. The first section 36 of this shaft is journalled in the stand 11 and hub 20 and presents at its 90 inner end a flange 37 fitting in the recess of a countersunk washer 38 which rests against the face of the shank. The outer end of this section 36 has clamped thereto the depending heel 34 by means of the set screw 39. The other section 40 of the shaft is journalled in the aperture of the fixed blade 22 and has an enlarged section 41 rigidly secured to the movable blade 28. A washer 42 and cotter pin 43 are mounted on the outer end of this 95

section and with the enlarged section 41 of the washer 42 prevent any endwise movement of this shaft section with respect to the fixed blade 22, except such as is necessary to permit the movable blade to be pressed against the fixed blade. The shaft section 40 is provided with a flat tongue 44 fitting in a correspondingly shaped recess 45 in the shaft section 36 so that the two shaft sections 10 will rotate together but may be laterally separated.

It will thus be seen that with the mechanism thus far described, the lay upon each beat-up will engage the depending heel 34, effecting the closing movement of the severing mechanism and that upon each retracting movement of the lay, the spring 33 will effect the opening movement of the severing mechanism. In order to obviate the continual 20 wear and tear upon the severing mechanism, which would thus be occasioned, provision is made for an intermittent operation, as a result of which the severing mechanism only operates when required, as when filling replenishment takes place. But in order to render such an intermittent operation fully effective, it is necessary to withdraw the closing means, as, for example, the depending heel 34, to a position where it will not be even 25 partially actuated or, as in the type of construction illustrated, entirely out of reach of the lay upon the beat-up. This latter result is secured in the present invention by making use of the relative sliding movement which 30 takes place between the temple stand and the temple shank at each beat-up of the lay. In the preferred construction illustrated, a ratchet wheel 46 is journaled on a stud 47 secured by a nut 48 in the shank parallel 35 with and above the shaft 21. Rigid with the ratchet wheel, and consequently rotatable therewith, is a locking lug 49 of such dimensions that when it is in locking position, as shown in Fig. 1, it will engage the extension 40 50 of the depending heel 34 and hold the depending heel forward of the temple heel 13 and consequently entirely out of reach of the lay. When in this position, the filling severing mechanism is closed and any actuation of 45 the filling severing mechanism is prevented. When the locking lug is turned away from locking position, the filling severing mechanism is restored to open position through the action of the spring 33. One of the teeth of 50 55 the ratchet wheel 46 is elongated at one face of the ratchet wheel to form a starter tooth 51. A suitable detent shown as a spring-pressed plunger 52 carried by the shank 11 acts to prevent reverse rotation of the ratchet wheel.

An actuating pawl for the ratchet wheel is mounted on the fixed stand 9. For this purpose a pawl-carrying lever 53 is fulcrumed at 54 on the stand. The actuating pawl 55 is in the form of a finger having its shank 56

adjustably mounted in the upper arm of the lever 53 by means of the set screw 57. The pawl carrying lever is movable about its fulcrum between an active and an inactive position. Its active position is determined by the set screw 58 adjustably mounted in the stand 70 and when in this position the pawl 55 will be in the path of the teeth of the ratchet wheel 46 as the shank 11 slides forwardly in the stand. The inactive position is limited by 75 the set screw 59 adjustably mounted in the stand and when in this position the pawl will pass above the teeth of the ratchet wheel upon the forward movement of the shank.

Suitable means are provided for moving 80 the pawl to active position and as it is desired that the filling severing mechanism shall operate upon filling replenishment in the case of an automatic filling replenishing loom, the arm 4 is utilized for moving the pawl to active 85 position as a preferred embodiment of this feature of the invention. The forward end of the lever 53 is bent downwardly as shown and cooperates with a spring-pressed detent pin 60 mounted in the stand. Normally this 90 pin rests against the upper surface 61 of the pawl carrying lever 53 holding the pawl in inactive position, and the end of the arm 4 is normally located just beneath the forward 95 end of the lever 53. Upon the call for filling replenishment, the shaft 3 is rocked, swinging the arm 4 to the left, thus snapping the lever 53 upward past the detent pin 60, which then engages the surface 62 and holds the 100 pawl in active position.

Assuming now that the parts are in the position shown in Fig. 1, it will be seen that the filling severing mechanism is closed, the depending heel 34 is well forward of the temple heel 13 and consequently out of reach of the 105 lay upon the beat-up, the locking lug 49 is holding the parts in this position, the actuating pawl 55 is in inactive position and the detent 60 is holding the pawl carrying lever with the pawl in such position. While the 110 parts are in this position, each time the lay beats up, it engages the heel 13 and moves the stand 11 with the parts carried thereby forward, but since the depending heel 34 cannot be reached by the lay, there is no operation 115 of the filling severing mechanism and no wear thereupon.

When, however, the call comes for filling replenishment, the arm 4 swings to the left, throwing the pawl carrying lever to active 120 position, and upon the next beat-up of the lay the starter tooth 51 engages the pawl 55, the ratchet wheel is rotated, the depending heel 34 is unlocked, and the filling severing mechanism moves to open position. Upon each succeeding beat-up, the filling severing mechanism is actuated because the lay now engages the depending heel 34 and the ratchet wheel is rotated step by step by the pawl. This 125 operation continues with the filling severing 130

mechanism operating at each beat-up until the rotation of the ratchet wheel has again brought the locking lug 49 into locking position. But when the locking lug comes into locking position, the starter tooth comes beneath the pawl so that upon the next rearward movement of the shank, the pawl is thrown upward by the starter tooth sufficiently to cause the forward end of the pawl carrying lever to snap down past the detent pin 60 and bring the pawl carrying lever and pawl to inactive position. Thereupon the parts are again in the position shown in Fig. 1.

Thus it will be seen that each time the locking lug is released, the filling severing mechanism acts for a predetermined number of times, depending upon the number of teeth on the ratchet wheel and the angular rotation given to the ratchet wheel by the pawl. Upon the conclusion, therefore, of a predetermined number of beat-ups, the intermittent action ceases and the filling severing mechanism is locked in closed or inoperative position with the closing means withdrawn from actuation or from engagement by the lay. It will also be seen that these results are secured by the making use of the relative sliding movement which takes place between the temple shank and the stand in which it is mounted. It will further be seen that all of this is effective quite independently of the bodily lateral position of the filling severing mechanism with respect to the selvage of the cloth.

Having thus described the invention, what is claimed as new, and desired to be secured by Letters Patent, is:

1. A thread cutting loom temple comprising a stand, a shank slideable rearward in the stand by a spring and forward by the lay on the beat-up, filling severing mechanism mounted on the shank, means acting to open said mechanism, means engaged and actuated by the lay upon the beat-up to close said mechanism, and means actuated by the relative sliding movement of the stand and shank to withdraw said closing means from engagement by the lay and lock it in withdrawn position after a predetermined number of beat-ups.

2. A loom comprising a frame, a lay and means for moving it, an arm on the frame moved upon the call for filling replenishment, a temple stand on the frame, a shank slideable forward in the stand by the lay on the beat-up, a spring acting to slide the shank rearward, filling severing mechanism mounted on the shank, means acting yieldingly to open said mechanism, means engaged and actuated by the lay upon the beat-up to close said mechanism and thereby sever filling ends in its field, means actuated by the forward sliding movement of the shank to withdraw said closing means from engagement by the lay and lock it in withdrawn position after a predetermined number of beat-ups.

3. A loom comprising a frame, a lay and means for moving it, an arm on the frame moved upon the call for filling replenishment, a temple stand on the frame, a shank slideable forward in the stand by the lay on the beat-up, a spring acting to slide the shank rearward, filling severing mechanism mounted on the shank, means acting yieldingly to open said mechanism, means engaged and actuated by the lay upon the beat-up to close said mechanism and thereby sever filling ends in its field, and means actuated by the relative sliding movement of the stand and shank to withdraw said closing means from engagement by the lay and lock it in withdrawn position after a predetermined number of beat-ups and to restore said closing means to actuation through the movement of the arm upon the call for filling replenishment.

4. A thread cutting loom temple comprising a stand, a shank slideable in the stand by the lay on the beat-up, filling severing mechanism mounted on the shank, a ratchet wheel journaled on the shank having a starter tooth and a locking lug which when in locking position acts to hold the severing mechanism in inoperative position, an actuating pawl mounted on the stand and movable between an active and an inactive position, and means to move the pawl to active position where, upon forward sliding movements of the shank, the pawl will rotate the ratchet wheel step by step turning the locking dog away from locking position and, after a plurality of said forward movements, bringing the locking lug to locking position and the starter tooth beneath the pawl, the said starter tooth upon the succeeding rearward sliding movement of the shank acting to move the pawl to inactive position.

5. A thread cutting loom temple comprising the construction defined in claim 4, together with means for yieldingly retaining the pawl in each of its two positions.

6. A thread cutting loom temple comprising a stand, a shank slideable in the stand by the lay on the beat-up, filling severing mechanism mounted on the shank, a ratchet wheel journaled on the shank having a starter tooth and a locking lug which when in locking position acts to hold the severing mechanism in inoperative position, a pawl carrying lever pivoted on the stand and movable between an active and an inactive position, a pawl adjustably mounted in the pawl carrying lever, means to swing the pawl carrying lever to active position where, upon forward sliding movement of the shank, the pawl will rotate the ratchet wheel step by step turning the locking dog away from locking position, and after a plurality of said forward movements, bringing the locking lug to locking position and the starter tooth beneath the pawl, the said starter tooth upon the succeeding rearward sliding movement of the

shank acting to move the pawl carrying lever and pawl to inactive position.

7. A thread cutting loom temple comprising a stand, a shank slidable in the stand and having a depending heel to be engaged by the lay on the beat-up to effect the forward sliding movement of the shank, filling severing mechanism mounted on the shank, a shaft having a depending operating heel in the path of and moved by the lay on the beat-up to actuate the filling severing mechanism, means for bodily adjusting the filling severing mechanism laterally with respect to the shank and the depending operating heel, and means actuated by the relative sliding movement of the stand and shank to withdraw said heel from the reach of the lay and lock it in said withdrawn position after a predetermined number of beat-ups.

20 8. A thread cutting loom temple comprising a stand, a shank slidable in the stand by the lay on the beat-up, filling severing mechanism mounted on the shank and having a depending operating heel in the path of and moved by the lay on the beat-up to actuate said mechanism, and means actuated by the relative sliding movement of the stand and shank to withdraw said heel from the reach of the lay and lock it in said withdrawn position after a plurality of beat-ups.

30 9. A thread cutting loom temple comprising a stand, a shank having a depending heel and slidable rearward in the stand by a spring and forward by the engagement of the lay with the heel on the beat-up, filling severing mechanism mounted on the shank and having a depending heel in the path of and moved by the lay on the beat-up to actuate said mechanism, and means actuated by the relative sliding movement of the stand and shank to withdraw said latter heel to a position forward of the former heel out of reach of the lay and to lock it in said withdrawn position after a plurality of beat-ups.

40 45 In testimony whereof, I have signed my name to this specification.

HORACE H. BURDETT.
